OIL WELL CASING

Howard G. Texter, Tulsa, Okla., assignor to The
National Supply Company, Pittsburgh, Pa., a
corporation of Pennsylvania

Application August 7, 1936, Serial No. 94,779

10 Claims. (Cl. 166—4)

This invention relates to well casing programs, and more particularly to the construction of oil well casing strings formed of a plurality of lengths of pipes connected end to end by threaded joints.

In drilling deep wells, such as oil wells, the usual practice is to estimate the depth to which the well must be drilled and the number of casing seal-offs between the surface and the final depth. The desired finishing hole size is then selected and provision is made for the number of nested casing strings to provide the seal-offs and the starting drill size is thereby determined. Drilling is commenced with the selected starting size and proceeds until it becomes necessary to seal off the hole with the outer or largest string of casing. This first seal-off operation may be necessary to seal off surface water, for example, after the well has been drilled from 100 to 1000 feet deep. Lengths of the outer casing are progressively connected together and lowered into the hole until the entire hole is lined with the casing string. The string of casing thus provided is usually sealed off by pumping cement down into the well, which flows up around outside of the casing and sets, thereby sealing and anchoring the casing firmly in place.

Drilling is then continued through the outer or largest diameter string of casing with a bit which will pass through the casing and with this second size of bit the well may go, for example, to 6500 feet where it again becomes necessary to seal off gas, water, sliding shale, or the like. The second string of casing is then progressively made up and lowered into the well through the first string and is sealed off in the same manner as the first. Drilling is continued in this manner with any number of additional seal-offs necessary (usually the estimated number) until the well has been drilled to the desired depth, at which time the final or inner string of casing of the smallest diameter is run in and sealed off in the same fashion as the other strings of casing. Usually each of the strings of casing extends to the top of the well and a nested assembly of strings is formed which is called a casing program.

From the foregoing brief description of the usual process of casing an oil well it is seen that a casing program usually consists of a number of concentric strings of casing, and that these strings are of successively increasing length.

My invention applies particularly to long strings of casing and offers economies which increase as a direct function of the length of the string.

There are two limiting features which determine the proportions of a long string of casing of a given diameter. It is the general practice to determine first the thickness of the casing wall which is required to resist collapse at the bottom with a predetermined factor of safety, under the arbitrary assumption that the casing is closed at the bottom and contains only air, while the casing is immersed for its entire length in salt water. The second step is to determine the factor of safety with which the joints connecting the various individual pieces together will resist tension failure under the assumption that the entire length of the string is hanging in air and is supported by a joint located at the upper end of the string. This tension safety factor is usually made large enough to withstand a pull considerably greater than the weight of the entire string. Very heavy pulls are sometimes imposed on casing. Some of the occasions demanding heavy pulls are: (a) recovering casing which stuck in the hole while being run in, and failed to reach bottom; (b) recovering casing from a dry hole, i. e., a hole which failed to produce gas or oil; (c) recovering casing from an exhausted well. To cover these contingencies a large number of operators consider a tension safety factor of 2.5 advisable.

As a result of the many factors involved in the construction and use of oil well casing various parties concerned, functioning through the agency of the American Petroleum Institute (hereafter referred to as A. P. I.) have set up certain well-recognized standard specifications on casing setting depths, sizes, weights, joint constructions, and operating safety factors. These specifications cover the majority of the casing sizes commonly used in the United States. Sizes other than those listed by A. P. I. are manufactured but these sizes closely follow the A. P. I. specifications and are here considered as being of the same type. Tables are included in the A. P. I. specifications showing the lengths of strings that may be run using various factors of safety for both tension and collapse. In the past the practice has been to use the same grade of material and the same wall thickness throughout a casing string. This practice has in general been satisfactory but wells are now being drilled deeper and are more expensive and the operating organizations are paying more attention to costs. For the most economical casing practice in deep wells there are certain disadvantages in the A. P. I. type of casing joint.

The tensile efficiency of the A. P. I. type of

casing joint is low due to the reduced cross sectional area at the root of the pipe threads. The tensile efficiency of a casing joint is the percentage quotient found by driving the load at 5 which the joint will fail by the load at which the body of the casing will fail. Joint strength is the actual pull in pounds required to break a joint. Joint efficiency in accordance with A. P. I. specification is practically constant for the same size 10 of casing regardless of the various wall thicknesses (weight per foot) commonly used. Therefore the tensile joint strength of any one size and grade of casing is roughly directly proportional to the wall thickness. This means that 15 while a long string of light wall casing of a certain size and grade might be able to support itself, with a suitable safety factor it would have a lower safety factor if the bottom part of the string consisted of the same size pipe but with 20 a heavier wall. In order to increase the joint strength a few sizes of the A. P. I. type of casing have been made with upset pipe ends for use in emergencies. For general use this is not practical because of the increase in the outside diameter 25 of the joint which is highly undesirable due to the decreased clearances between the nested strings of casing forming a complete program. A re-establishment of the clearances would necessitate a larger starting casing and bit size, with 30 the attendant increase in drilling costs.

It is the object of my invention to avoid and overcome the foregoing and other difficulties of known casing practices as particularly exemplified in the use of A. P. I. casing by the provision of an improved casing program in which the individual casing strings are formed of certain combinations of individual lengths of casing whereby the program is better adapted to resist collapse and tensile pull while maintaining 40 the starting casing and drilling size at a minimum.

Another object of my invention is to provide a less expensive string of casing in which the resistance to collapse of the lower portions of the 45 string and the resistance to tensile pull in the upper portion of the string are well within the required factors of safety.

Another object of the invention is the provision of a casing string for lining an oil well in 50 which the actual strength of the joints connecting the individual casing lengths is independent of the wall thickness and is substantially constant for any given size and grade of material and wherein the weight per foot of the casing increases 55 downwardly from the top of the string and the efficiency of the joints connecting the individual casing lengths increases upwardly of the string at one or more stepped points.

The foregoing and other objects of the invention 60 are achieved by provision of a well-casing program including a plurality of nested strings of casing extending to progressively greater depths into the earth, at least one of said strings comprising a lower portion formed of connected individual 65 casing lengths having a suitable factor of safety against collapse, together with an upper portion connected to the lower portion and comprising individual casing lengths of less weight per foot than the lower portion, the joints between the 70 individual lengths of this upper portion are of approximately the same strength as the joints of the lower portion in the cases where both portions are of the same grade of material. In the cases where the upper portion can be made of 75 less expensive material the joint strength will

be less than that of the lower portion but in any case the joint efficiency of the upper portion will be greater than that of the lower portion so that a suitable factor of safety in tension is provided.

Referring to the drawings which quite diagrammatically illustrate the invention, Fig. 1 is a vertical cross-sectional view through a well and illustrating a casing program constructed in accordance with the principles of my invention; Fig. 2 is a view taken on line II—II but only partly in section of a typical joint construction particularly adapted for use in the practice of my invention; Figs. 3, 4, and 5 are transverse cross-sectional views taken respectively on lines III—III, IV—IV, and V—V of Fig. 1 and illustrate the decrease at vertically spaced points of the wall thickness of the casing without change in outside diameter or joint strength.

In the use of combination strings of casing in a well-casing program, as herein taught, the strength and dimensions of the joint connecting the individual casing lengths together is important. The joint must be capable of being constructed on pipe of the same outside diameter but of varying wall thickness so that the thinner wall casing has a greater joint efficiency (although the same strength) than any heavier wall casing and also so that complete interchangeability is provided between all joints regardless of the wall thickness of the pipe. A joint which is particularly adapted for use in the practice of my invention is that disclosed in United States Patent No. 1,927,656 to Eaton and Burnish and an improved form thereof is disclosed in United States Patent No. 2,062,407 to George M. Eaton. This joint is known in the trade under the name "Extreme line" and accordingly is so identified in the tables hereinafter forming a part of my specification. The casing or pipe body proper is the same as that of the A. P. I. standards but 40 an "Extreme line" joint is formed integral with the body as hereinafter more fully described, instead of the usual A. P. I. joint. The particular advantage of the joint which renders it available to the practice of my invention is that it is readily 45 adapted to be formed with substantially any desired joint efficiency and strength by establishing the proper upsetting, machining, and threading operations.

A joint of the Eaton type has been illustrated 50 in Figs. 2 to 5 of the drawings and includes threaded male and female portions 5 and 6 formed integrally with the casing lengths. In making this type of joint the pipe ends are upset 55 to provide the necessary thickness for the desired strength and are then machined to form the trapezoidal thread and sealing surfaces indicated. As hereinafter more fully explained, the casing of the joint of Figs. 2 and 3, like the remainder of the casing at the lower portion of 60 the string, is formed with relatively thick walls and a small inside diameter to provide a casing very resistant to collapse. The casing of the joint of Fig. 4, typical of the casing at the middle portion of the string, is of a medium wall thickness and a somewhat larger inside diameter, as will be 65 seen by comparing Figs. 3 and 4. The casing of the joint of Fig. 5, typical of that at the top of the string, is of a smaller wall thickness and a greater inside diameter and is formed with the 70 upset male portion 5 of the joint being of equal strength and radial thickness to the female portion 6 of the joint. In the three joints of Figs. 3 to 5 the outside diameter is the same and the joint strength (actual breaking strength in ten- 75

sile pull) is the same since the radial thickness of the female portion 6 is constant. The joint efficiency of the joint of Fig. 5 is greater than that of Fig. 4 which in turn is greater than that of Fig. 3, as will be evident.

5 of safety in collapse of less than 1.5. Sometimes where all conditions are favorable, a smaller factor of safety, as, for example, 1.25 or even less, has been used with success. Also, it is considered good practice to provide a factor of safety in tension of at least 2 to 2½.

By machining the inner and outer surfaces of the upset pipe end the dimensions of the joint are maintained within narrow limits and thus the clearances between nested casing strings are greater than with the A. P. I. type of joint so that in many instances the starting drilling size can be reduced.

Reference should now be had to Table I which contains data regarding some of the commonly used weights and grades of standard A. P. I. 10 7" outside diameter, well casing and the A. P. I. joint and also data concerning "Extreme line" joints constructed in accordance with the principles of my invention.

10 Referring again to Table I it will be seen that the 30.3 lb. Grade D, A. P. I. casing can be set to a depth of 8960 feet with a factor of safety in collapse of 1.5. Also 28.3 lb. Grade D, A. P. I. 15 casing can be set to 8090 feet and 24.3 lb. Grade D, A. P. I. casing to 6340 feet with a factor of safety in collapse of 1.5. These figures are calculated from tables published in A. P. I. Code No. 5, Supplement No. 1.

15 As previously explained, the general practice has been to use the same wall thickness and grade of material throughout the string, the safety factors in tension and collapse being based

5 cency connecting the individual lengths. The intermediate string of casing may extend 6500 feet or more into the well. The exact manner of selecting the individual casing lengths and associated joints for both the lower and upper portions of the casing string 14 will be described in greater detail hereinafter.

10 The casing string 16 extending from the top of the well clear down to the oil strata is made 10 in accordance with my invention with two or more portions of different weights and joint strengths all connected together to form a continuous casing string. For example, the lower portion 16a of the string is formed of connected 15 casing lengths particularly adapted to resist collapsing forces. A middle portion 16b is adapted to resist medium collapsing forces and medium tensile forces. The upper portion 16c is made of individual casing lengths and connecting joints 20 particularly adapted to resist tensile forces inasmuch as the joints of this portion of the string support the weight of the entire string. The casing lengths at the top of the string, however, need not be particularly strong so far as resistance 25 to collapse is concerned.

Particularly illustrating the manner of practicing my invention and the method of determining the combinations employed in each individual string of casing, Table II illustrates several typical examples of combination strings and the resulting casing program.

5 foot to casing of 40 lbs. per foot, but that the grade of the material used can be changed from Grade D to the less expensive Grade C. This is due particularly to the fact that I make the joint efficiency in the 40 lb. Grade C casing approximately 93 per cent so that the joints of Grade C casing are able to support the weight of the entire casing string.

10 The depth to which the 40 lb. Grade C casing is set is determined by the collapse setting depth 10 in the A. P. I. tables, and it is found that at a depth of 3500 feet the factor of safety is 1.71. Accordingly, by way of example, the string 14 shown in Fig. 1, constructed in accordance with the principles of my invention, may comprise an 15 upper portion 14b formed of 3500 feet of 40 lb. Grade C casing, having a joint efficiency of about 93 per cent and a factor of safety in tension of approximately 3.1 which is connected to and supports the lower portion 14a of the string formed 20 of 47 lb. casing, Grade D, which has a factor of safety in tension well above 3.1. The factor of safety in collapse of the 3000 feet of 47 lb., Grade D, forming the portion 14a of the casing string is approximately 1.54 and the factor of safety 25 against collapse of the upper portion 14b of the casing string formed of 40 lb. Grade C is approximately 1.71.

Example 1 of Table II likewise indicates that 30 the inner or smallest string 16 of casing is set to 10000 feet. The tables, such as Table I, are in-

TABLE II

35	Type	Example 1		Example 2		Example 3		Example 4		Example 5		36
		Extreme line	Extreme line	Extreme line	Extreme line	A. P. I.	A. P. I.	A. P. I.	A. P. I.	A. P. I.	A. P. I.	
40	Length of string feet	6500	10000	10000	11000	6500	10000	10000	10000	9000	9000	41
	Length feet	3500	4700	5300	5800					4300

		6500	2500	3500	3500					9000		
45	Depth set feet	3500	4700	4700	5800	6500	10000	10000	10000	4300	9000	41
	Depth set feet	6500	7500	7500	7500							
		10000	10000	11000	11000							
50	O. D. casing in	9 1/2	7	7	7	7	7	7	7	7	7	51
	O. D. casing in	9 1/2	7	7	7	7	7	7	7	7	7	
55	Weight of casing lbs. per foot	40	24	24	24	47.6	30	24	30.3			5
	Weight of casing lbs. per foot	47	28	28	28							
			30	30	30							
	Grade of casing (A. P. I.)	C	C	C	D	D	D	C	D			
	Grade of casing (A. P. I.)	D	D	D	D							
60	Factor of safety collapse	1.71	1.6	1.6	1.64	1.54	1.34	1.75				6
	Factor of safety collapse	1.54	1.62	1.21	1.62			1.49				
			1.34	1.22								
	Factor of safety tension	3.1	2.08	2.12	2.43	2.76	1.74	1.38				

65 In Example 1 it is found necessary to set casing having an outside diameter of 9 1/2" to the depth of 6500 feet. This string of casing might, for example, be the intermediate string 14 shown in Fig. 1 of the drawings. Looking into the A. P. I. tables we find that 9 1/2" O. D. and 47 lbs. per foot can be set to 6500 feet with a safety factor of 1.54.

70 Now instead of running 47 lb. casing for the entire 6500 feet to which it is to be set, I have discovered that by using the "Extreme line" joint and making it of the proper strength and efficiency, not only can the wall thickness of the casing be reduced in its upper portion, as, for example, by changing from casing of 47 lbs. per

vestigated to determine the necessary weight and grade of 7" casing which can be set to 10000 feet. The table indicates that 30 lb. Grade D can be set to 10000 feet with a factor of safety in collapse of 1.34. Also in 7" casing, 24 lb. Grade C, can be set with a factor of safety in collapse of 1.6 to 4700 feet. Twenty-eight pound Grade D casing can be set to 7500 feet with a factor of safety in collapse of 1.62. As a result of these figures and in accordance with the principles of my invention I form string 16 of an upper portion 16c formed of 4700 feet of 24 lb. Grade C casing having a factor of safety against collapse of 1.6. To the bottom of this upper portion of the string is secured the middle portion 7

5 of 16b of 2800 feet (7500-4700) of 28 lb. Grade D casing which as above stated can be set to 7500 feet and still provide a factor of safety against collapse of 1.62. The bottom or lower portion 16a of the string 16 is formed of 2500 feet (10000-7500) of 30 lb. Grade D casing which has a factor of safety against collapse of 1.34 at 10000 feet.

10 Checking the factor of safety in tension of the upper portion 16c of the combination string, I find that it is approximately 2.08, which is satisfactory. The relatively high factor of safety in tension of the upper portion 16c of the combination string is due to the high joint efficiency which 15 compensates amply for the lower grade and less weight-per-foot casing employed.

In this manner I am able to reduce the cost of the casing program without reducing the factor of safety of the casing in tension and collapse 20 and without increasing the starting drilling size.

Example 2 in Table II indicates a combination string set to 10000 feet in which the upper portion 25 of the string comprises 4700 feet of 7"-24 lb. Grade C casing having a factor of safety in tension for the complete string of at least 2.12 and a factor of safety in collapse of at least 1.6. The bottom or lower portion of the string comprises 5300 feet of 28 lb. Grade D casing having a factor of safety in collapse of at least 1.21. Since much 30 less tensile weight is carried by the lower portion of the casing the factor of safety in tension will of course be far above 2.12.

Example 3 in Table II illustrates my method of setting 7" casing to the depth of 11000 feet while 35 providing a safety factor in collapse of at least 1.2. In this embodiment of the invention 24 lb. Grade D casing is set to the depth of 5800 feet and provides a safety factor in collapse of 1.64. Connected to the bottom of the 24 lb. casing is 40 1700 feet of 28 lb. Grade D casing having a safety factor in collapse of 1.62. Secured to the bottom of the 28 lb. casing is 3500 feet of 30 lb. Grade D casing which has a safety factor in collapse of 1.22. The joint efficiency of the 24 lb. casing is 45 97 per cent, the 28 lb. casing 87 per cent, and the 30 lb. casing 81 per cent. The actual joint strength in each case is approximately the same, namely, about 690,000 lbs. With the total weight 50 of the combination string approximately 300,000 lbs. the factor of safety in tension is at least 2.25.

Example 4 of Table II is illustrative of the standard method of using A. P. I. casing to provide the strings of casing given in Example 1. It 55 will be recognized that the use of A. P. I. casing necessitates the selection of heavier pipe to obtain the same factors of safety. As a matter of fact, the difference in weight of the string 14 of Example 1 and the first string of Example 4 is 60 $(3500 \times 40 - 3000 \times 47.6 - 6500 \times 47.6)$ 18400 pounds. However, the factor of safety in collapse is the same in both strings (1.54) and the factor of safety in tension is greater (3.1 against 2.76) in my combination string. Moreover, in my combination string, less expensive metal (Grade C as 65 against Grade D) is employed for over half the casing.

Likewise, string 16 of Example 1 and the same string of Example 4 have a difference in weight 70 of 33,800 pounds

$(4700 \times 24 - 2800 \times 28 - 2500 \times 30 - 10000 \times 30)$.

Yet the factor of safety in collapse is the same in both strings (1.34) and the factor of safety in tension in my improved string is greater (2.08 75

against 1.74). Grade C material is also used in part of my combination string.

It will therefore be recognized that I have materially reduced the weight of a casing string and the grade of material employed in part of the 5 string and still have not lowered, but in most cases have improved, the factor of safety of the string. The result is a less expensive and a more satisfactory casing string and program.

Example 5, Table II, discloses the use of A. P. I. 10 casing while practicing certain of the principles of the invention to provide a composite or combination string of casing similar to that disclosed in Example 3, except that the string is only 9000 feet long. However, the factor of safety in tension 15 has dropped dangerously low.

While the standard A. P. I. threaded joint is 20 relatively easy and inexpensive to manufacture, it is open to numerous objections which have been listed in detail in the Eaton patents referred to above. However, in proposing an improved form of well-casing joint it is necessary not only to 25 overcome the inertia of the public's slowness to accept a new product, but also to compete, if possible, on a price basis with the old product, even though the new is superior. An important 30 feature of my invention resides in the savings effected by the use of combination strings whereby a joint of the Eaton type, when constructed 35 as herein disclosed, can not only compete with the standard A. P. I. joint but can often show definite savings in casing costs. This is due 40 chiefly to the fact that the weight of the casing can be reduced upwardly of the string and a cheaper grade of material can be employed without reducing the factor of safety in collapse or in tension to points below the necessary minimums. The lighter weight casing of cheaper 45 grade forming the upper portions of my proposed combination strings is provided with joints of greater efficiency than the joints in the lower portions and of ample strength so that the factor of safety in tension is maintained.

It should be appreciated, however, that in certain 50 instances some of the advantages of my invention are obtained by the practice of the principles thereof with ordinary A. P. I. casing or other casing not having special high strength joints. Use in this manner is limited to conditions where the ordinary casing has sufficient 55 strength in tension and collapse to effect the desired end.

It will be seen from the foregoing that the 60 objects of the invention have been achieved by the provision of an improved type of casing program in which the individual nested strings of casing are formed of combinations of interchangeable lengths of casing possessing different 65 properties such as pounds per foot, material used, and joint efficiency. The invention provides for maintaining the factor of safety against collapse and in tension at relatively high and satisfactory levels while noticeably reducing the cost of the casing program, as well as insuring the smallest 70 possible drilling size for the largest finishing size. Under the teachings of my invention the casing program for any well is easily planned by the man skilled in the art and comprises the first scientific casing program utilizing the strength of the metal 75 therein more efficiently than was the general practice prior to my invention.

While in accordance with the patent statutes one embodiment of the invention has been illustrated and several described in detail, the inven- 76

tion is not limited thereto or thereby but is defined in the appended claims.

I claim:

- 5 1. A well casing string comprising a lower portion formed of connected individual casing lengths having a factor of safety in collapse of at least about 1.25 and an upper portion of connected individual casing lengths of less weight per foot than the lower portion but having joints 10 between the individual lengths of approximately the same tensile strength as the joints of the lower portion but of an appreciably higher tensile joint efficiency so that the factor of safety in tension of the joints in the upper portion of the 15 string is at least approximately 2.
2. A well casing string comprising a lower portion formed of thread-connected individual casing lengths having relatively heavy walls adapted to resist collapse and an upper portion of thread-connected individual casing lengths of lighter walls than the lower portion but having joints 20 between the individual lengths of a higher efficiency but with approximately the same tensile strength as the joints of the lower portion of the 25 casing.
3. A well casing string comprising a lower portion formed of thread-connected individual casing lengths particularly adapted to resist collapse and an upper portion of thread connected individual casing lengths of less weight per foot than the lower portion but having the individual 30 lengths of casing connected by joints approaching 100% tensile efficiency so that the factor of safety in tension of the joints in the upper portion of the 35 string is at least approximately 2.
4. A well casing string formed of individual lengths of casing connected together by threaded joints at their ends, said string including a lower portion adapted to resist collapse, an intermediate portion of less weight per foot than the lower portion and adapted to resist intermediate collapsing pressures and medium tensile pull, and an upper portion of less weight per foot 40 than the intermediate portion and adapted to resist low collapsing pressures and high tensile pull, the strength of the joints in tension throughout the string being substantially constant but with the tensile joint efficiency of the upper portion being approximately 90% or more, the tensile 45 joint efficiency of the lower portion being approximately 70% or more, and the tensile joint efficiency of the intermediate portion being in between the efficiencies of the upper and lower portions.
5. A well casing string formed of individual lengths of casing connected together by joints, said string including a lower portion particularly adapted to resist collapse, an intermediate portion particularly of less weight per foot than the lower portion and adapted to resist intermediate collapsing pressures and medium tensile pull, and an upper portion of less weight per foot than the intermediate portion and particularly adapted to resist low collapsing pressures 60 and high tensile pull, the strength of the joints in tension throughout the string being substan-
6. A well casing string formed of individual lengths of casing connected together by threaded joints, said string including a lower portion having a factor of safety against collapse of not less than 1.25, an intermediate portion of thinner walls having a factor of safety against collapse of not less than 1.25, and an upper portion having thinner walls than the intermediate portion and a factor of safety against collapse of not 15 less than 1.25, the strength of the joints in tension throughout the string being substantially constant but with the tensile joint efficiency increasing at stepped points upwardly of the string. 10
7. A well casing string formed of individual lengths of casing connected together by joints at their ends, said string including a lower portion having relatively thick walls adapted to resist collapse, and an upper portion having thinner walls adapted to resist lower collapsing pressures, 25 the tensile joint efficiency of the upper portion being not less than approximately 90%, and the tensile joint efficiency of the lower portion being lower than about 90%. 20
8. A well casing string comprising a lower portion formed of connected individual casing lengths having a factor of safety in collapse of at least about 1.25, means joining the lengths together, an upper portion of connected individual casing lengths of less weight per foot than the lower portion, means joining the individual lengths of the upper portion of the string together and having approximately the same tensile strength as the means joining the casing 30 lengths of the lower portion together so that the factor of safety in tension of the joining means in the upper portion of the string is at least approximately 2. 35
9. A well casing string comprising a lower portion formed of thread-connected individual casing lengths particularly adapted to resist collapse, and an upper portion of thread-connected individual casing lengths of less weight per foot than the lower portion but having the individual lengths of casing connected by joints approaching 100% tensile efficiency so that the factor of safety in tension of the joints in the upper portion of the string is at least 1.5. 45
10. A well casing string comprising a lower portion formed of connected individual casing lengths particularly adapted to resist collapse and an upper portion of connected individual casing lengths of less weight per foot and different grade than the lower portion but having the individual lengths of casing connected by joints approaching 100 per cent tensile efficiency so that the factor of safety in tension of the joints in the upper portion of the string is at least 60 approximately 2. 55
